LIGHT STANDARD OR SIMILAR ARTICLE

Robert W. Selden, Seattle, Wash., assignor to
Weyerhaeuser Company, Tacoma, Wash.

Original design application Oct. 20, 1969, Ser. No.
19,636, now Patent No. 220,531, dated Apr. 20,
1971. Divided and this application Aug. 24, 1970,
Ser. No. 24,651

Term of patent 14 years

Int. Cl. D26—03

U.S. Cl. D48—31

Fig. 1.

Fig. 2.

Fig. 8.

Fig. 9.

FIG. 1 is a front elevational view of a light standard or similar article illustrating my new design.

FIG. 2 is an elevational view thereof, offset 45° from the view in FIG. 1.

FIG. 3 is a cross-sectional view taken on line 3—3 of FIG. 1.

FIGS. 4, 5, 6 and 7 are cross-sectional views of further embodiments of my design, being taken on the same plane as line 3—3 in FIG. 1, the embodiments being identical to the embodiment of FIG. 1, except in cross-section.

FIG. 8 is a front elevational view of a further embodiment of my design.

FIG. 9 is an elevational view thereof, offset 45° from the view in FIG. 8.

FIG. 10 is a cross-sectional view taken on line 10—10 of FIG. 8.

FIGS. 11, 12, 13 and 14 are cross-sectional views of further embodiments of my design, being taken on the same plane as line 10—10 in FIG. 8, the embodiments being identical to the embodiment of FIG. 8, except in cross-section.

The lamps are shown in broken lines in FIGS. 1-2 and 8-9 for illustrative purposes only.

This is a division of design application Ser. No. D. 19,636, filed Oct. 20, 1969, now design patent No. D. 220,531.

I claim:

The ornamental design for a light standard or similar article, as shown and described.
